United States Patent Office

Des. 187,190
Patented Feb. 9, 1960

187,190

PLATE OR SIMILAR ARTICLE

Shigeru Masuda, Nagoya, Aichi, Japan, assignor to Noritake Co., Inc., New York, N.Y., a corporation of New York

Application August 24, 1959, Serial No. 57,277

Term of patent 7 years

(Cl. D44—15)

Fig. 1

Fig. 2

Fig. 1 is a plan view of a plate or similar article, showing my new design; and

Fig. 2 is a view showing a segment of the border of the plate to enlarged scale to show details of my design.

The plate is of a conventional configuration when viewed from the side and bottom thereof.

I claim:

The ornamental design for a plate or similar article, substantially as shown and described.
